CLAIM

The ornamental design for an electric vehicle charging station with movable swing arms, as shown and described.

DESCRIPTION

FIG. 1 shows a front perspective view of an electric vehicle charging station with movable swing arms;

FIG. 2 shows a front view of the electric vehicle charging station with movable swing arms of FIG. 1;

FIG. 3 shows a back view of the electric vehicle charging station with movable swing arms of FIG. 1;

FIG. 4 shows a right view of the electric vehicle charging station with movable swing arms of FIG. 1;

FIG. 5 shows a left view of the electric vehicle charging station with movable swing arms of FIG. 1;

FIG. 6 shows a top view of the electric vehicle charging station with movable swing arms of FIG. 1;

FIG. 7 shows a bottom view of the electric vehicle charging station with movable swing arms of FIG. 1;

FIG. 8 shows a rear perspective view of the electric vehicle charging station with movable swing arms of FIG. 1;

FIG. 9 shows a front perspective view of the electric vehicle charging station with movable swing arms of FIG. 1 where the bottom movable swing arm is moved to an extended position;

FIG. 10 shows a front view of the electric vehicle charging station with movable swing arms of FIG. 1 where the bottom movable swing arm is moved to the extended position shown in FIG. 9;

FIG. 11 shows a front perspective view of the electric vehicle charging station with movable swing arms of FIG. 1 where the top movable swing arm is moved to an extended position; and,

FIG. 12 shows a front view of the electric vehicle charging station with movable swing arms of FIG. 1 where the top movable swing arm is moved to the extended position shown in FIG. 11.

The broken lines illustrate environmental structure and form no part of the claimed design.
